UNITED STATES PATENT OFFICE.

WILLIAM E. LEIBING, OF OAKLAND, CALIFORNIA, ASSIGNOR TO MAGNUS FRUIT PRODUCTS CO., OF SAN FRANCISCO, CALIFORNIA, A CORPORATION OF CALIFORNIA.

COOLING APPARATUS FOR BEVERAGE DISPENSERS.

Application filed November 5, 1927. Serial No. 231,222.

This invention relates to improvements in mechanical refrigerating apparatus, and more particularly to an apparatus arranged and designed for positioning within beverage dispensing containers of the type commonly termed "root beer dispensing apparatus".

In beverage dispensing apparatus of the above type, there is generally provided one or more syrup supplies, a supply of carbonated water, and a supply of sweet or fresh water, and it is to maintain these supplies of syrup, carbonated water, and sweet or fresh water at the desired temperature by a self contained mechanical refrigeration apparatus that the present invention is designed.

One of the principal objects of this invention is in the arrangement of the respective parts within the dispensing apparatus or receptacle whereby the refrigerating unit, preferably through conduction, controls the temperatures of the fluids within the apparatus; another object is to arrange the interior chambers or compartments of the apparatus in such manner that accessibility is easily had to the units for repairing, cleaning, re-filling or any other purpose.

A further object is to provide a beverage dispensing apparatus of the above type adaptable for use in rural districts where electricity is available, and which will, without the necessity of a delivery service of manufactured ice, enable the proprietor to dispense a cool thirst quenching beverage either in the form of a mixed drink, carbonated water, or plain water. Another object is to provide a structure of the above type which may be cheaply manufactured and operated at little cost; and wherein the temperatures of the respective dispensed fluids can be maintained at any desired degree. Other objects and advantages of the invention will appear as the specification proceeds.

With the above and other objects in view, the invention consists in the novel construction and combination of parts hereinafter described, illustrated in the accompanying drawings, and set forth in the claim hereto appended, it being understood that various changes in the form, proportion, size and minor details of construction within the scope of the claim may be resorted to with-

out departing from the spirit or sacrificing any of the advantages of the invention.

To more fully comprehend the invention, reference is directed to the accompanying drawings wherein:

Fig. 1 is a view in vertical section of one embodiment of my invention as applied to the conventional root beer dispensing apparatus.

Fig. 2 is a transverse sectional view taken on line 2—2 of Fig. 1, viewed in the direction of the arrows.

Fig. 3 is a view in transverse detail section through the brine well and the interconnected cylinders illustrating in dotted lines or phantom the frost or ice layer of fresh water, built up on the surface of the brine well and extending to the fresh water coil and the vertical cylinders.

Referring more particularly to the drawings, wherein like characters of reference designate corresponding parts, 1 indicates a suitable dispensing apparatus illustrated in the form of a cylindrical container having a removable cover 2. Externally of the container, preferably mounted thereon, is a suitable mixing faucet or valve 3, conventionally illustrated and of a type well known in the art capable of handling a number of fluids either singly or in mixed relation.

Resting on and extending upright from the base of the container is a unit 4 for carbonated water consisting of the interconnected cylinders 4' arranged in arcuate formation and provided with the carbonated water inlet 5 and the outlet 7 connected through pipe 8 with the valve 3.

The end cylinder 4' of the unit 4 is connected with a supply of fresh water 6, and from the cylinder extends a fresh water coil 9, the latter surrounding the group of cylinders and connects through a pipe 10 with the valve 3.

Supported in any suitable manner within the interior of the container and preferably on the rear thereof, as in Fig. 2, is a suitable tank 11 formed with a depending well 12 preferably arcuate in plan, as in Fig. 3, with its forward wall lying in spaced relation to the group of cylinders. The tank 11 houses a suitable refrigerating unit, coil, or boiler 11' of any of the well known types employed in mechanical refrigerators, and with the same connect the pipes 14 and 15.

extending exteriorly of the container 1, and connecting respectively with the condenser 16 and compressor 17 of the conventional mechanical refrigerating plant.

5 The tank 11 and well 12 contain a brine or other refrigerating solution 18 and the preferred level of which is sufficiently high in tank 11 to envelop the unit 11', as illustrated in Fig. 1.

10 Resting on and supported by tank 11 is a syrup container or receptacle 19 illustrated as having an open top, the tank connecting with the valve 3 through a pipe 20.

15 As illustrated, the container 1 is normally filled to the approximate level of the top of the unit 4 with fresh or sweet water 21, the tank 11 with the brine 22, and the syrup container with syrup 23. With the parts arranged as described and illustrated and 20 with the motor 24 operating to actuate the compressor 17, and with the temperature regulator (not shown) set to cause the mechanical refrigerating apparatus to operate and cease operating between fixed temperatures, the action of the apparatus is as follows: The lowered temperature of the refrigerating unit 11' removes the heat from the brine 22, and causes the temperature thereof to drop below the freezing point of 25 fresh water. The low temperature of the brine 22 in well 18 is conducted through the well walls and causes a zone of low temperature preferably below freezing to build up around the well 12, and at the same time 30 reducing the entire temperature of the body of fresh water 21. The fresh water immediately adjacent to and surrounding the well 12 will be reduced to the lowest temperature of the body of fresh water 21, and this 35 water surrounding the well 12 will build up in the form of an ice or brine layer 25 of a thickness depending on the setting of the temperature regulator, it being preferable to have the temperature regulator set 40 sufficiently low that this ice or brine layer will extend to the units 4 and coil 9, as indicated in Fig. 3.

45 It will thus be observed that the syrup

23 in tank 19 is maintained cool by conduction from brine solution 22, also that the 50 carbonated water and fresh water in the solution are maintained at a relatively low temperature by the frost or ice layer 25 which forms around the well 12.

55 The arrangement of the various parts, as illustrated, within the container 1, enables the inspection, removal and repair of the unit 4 without disturbing the elements 19, 11, 11' or 12, and also enables the removal of the syrup tank independently of these 60 units, and without interfering with the unit 4. While the unit 4 has been described as one form of a carbonator cooler, it is to be understood that other forms of coolers or carbonators may be employed and positioned within the unit 1, just so long as the same are adapted for use in an apparatus of the described type.

I claim:—

A cooling apparatus for liquid dispensers 70 comprising a container provided with an open top, said container provided with a body of liquid therein, a tank supported within said container at one side and extending into said liquid body, said tank 75 containing a body of brine, a refrigerating unit within the tank immersed in the brine solution therein, a unit positioned within said container in front of said tank, a second unit positioned within said container, 80 said units being removable from the container independently of the tank and through each of which units a separate body of liquid passes, said units lying adjacent to said tank whereby the temperature of the 85 fluid passing therethrough is controlled by conduction from said brine solution through said body of fresh water, a fluid receptacle lying above and supported by said tank, a mixing valve exteriorly of the container, 90 and independent pipes extending from the units and receptacle to said mixing valve.

95 In testimony whereof I have signed my name to this specification.

WILLIAM E. LEIBING.
